A. G. LARSON

AIR COMPRESSOR

Filed Dec. 15, 1925

UNITED STATES PATENT OFFICE.

ALBERT G. LARSON, OF PIEDMONT, CALIFORNIA.

AIR COMPRESSOR.

Application filed December 15, 1925. Serial No. 75,496.

- This invention relates to compressors, particularly air compressors. In compressors heretofore devised, it has been common practice to mount both the intake and exhaust valves in the head directly over the cylinder end. This practice is objectionable for various reasons. Such construction necessarily limits the size of these valves, making them inefficient in operation.
- Also, it is particularly objectionable to mount the intake valve in this manner, since the valve stem occasionally breaks or the threads thereon become worn and permit the valve to drop directly into the cylinder, thus causing considerable damage. It is an object of my invention to provide a compressor in which only the exhaust valve is mounted in the head over the cylinder, the intake valve being mounted in the body of the compressor. I am aware that ball valves have been heretofore mounted in a similar manner, but such construction is inefficient and objectionable for reasons hereinafter stated.
- My improved compressor uses the well known pocket or plunger valve which is most efficient in machines of this type. I mount the exhaust valve in the head of the compressor and the intake valves in the body of the compressor between two adjacent cylinders thereof, a common intake port preferably being provided for both intake valves and a communication being provided from each intake valve to its cylinder by grooving the adjacent faces of the body and head of the compressor.
- It is another object of my invention to provide an improved compressor of this type.
- A further object of my invention resides in the provision of an improved arrangement of cooling fans for the compressor. In accordance with this feature of the invention, I mount a fan shaft in a bearing extending transversely of the compressor between two adjacent cylinders thereof and preferably mount two fans respectively on the ends of this shaft at opposite sides of the compressor.
- In the accompanying drawing I have illustrated certain specific embodiments of my invention, but it will be understood that the invention can be otherwise embodied and that the drawing is not to be construed as defining or limiting the scope of the invention, the claims appended to this specification being relied upon for that purpose.
- Referring to the figures of the drawing,
- Figure 1 is a longitudinal sectional view through my compressor taken on line I—I of Fig. 4.
- Figure 2 is a transverse sectional view thereof taken on line II—II of Fig. 4.
- Figure 3 is partial plan view.
- Figure 4 is a plan view with the head removed.
- In the drawing, 1 indicates the crank case, 2 the body, and 3 the removable head of my compressor. Pistons 4 operating in cylinders 5 are connected to the crank shaft 6 by pitmans 7.
- An opening 8 is provided through the head 3 into each cylinder. The bottom of each such opening is formed into a valve seat for receiving a valve 9 having a stem 10 guided within a closure plug 11 threaded into the opening. A spring 12 is provided for normally holding each valve in its closed position. Outlet ports 13 are provided from the chambers 8.
- The inlet valves 14 are provided in the body 2 between the cylinders. Each of these valves rests on a seat over an opening in communication with a common intake port 15. The stems 16 of these valves are guided in holes in the head 3. Springs 17 normally hold the valves closed. As illustrated, both cooperating faces of the body and head are grooved to provide ports 18 leading from the intake valves to the cylinders. The air or gas to be compressed is brought in by a pipe 19.
- Directly beneath the port 14 I provide a shaft bearing through the body 1 between the two adjacent cylinders and I mount a fan shaft 20 in this bearing. The shaft may be driven by a belt 21 running over a pulley 22. The fans 23 on the opposite ends of the shaft at opposite sides of the compressor are adapted to very efficiently cool the compressor upon rotation of the shaft.
- It is believed that the advantages of my invention will be obvious. The several cooperating parts of the compressor are extremely simple and so mounted as to be most readily accessible. The exhaust valves 9 are readily accessible for repairing or grinding

the valve seats merely by removing the plugs 11. The intake valves 14 are readily accessible by removing the head 3.

The form of valves used may be the 5 tapered valve shown in the drawing or flat disk valves. Such type of valve permits of a very large valve opening beneath the valve seat without adding greatly to the weight 10 of the valve and without requiring additional valve space above the valve seat. This is not true of ball valves, since increasing the diameter of the ball of such a valve greatly increases the weight and height of the ball. It will be noted that the valve openings at 15 the ends of the cylinders are relatively large, being nearly the size of the cylinders. This construction adds greatly to the efficiency of the compressor and cannot be attained where both the inlet and outlet valves are located 20 at the end of the cylinder. Furthermore, there is no danger of the valve dropping down into the cylinder as is the case when the intake valve is mounted in the head as heretofore described.

25 The location and arrangement of the intake valves 14 provide not only an efficient construction, but also a construction very easy and cheap to manufacture. A single intake port 15 is provided for both valves 30 and the size of the valves can be as large as desired. The ports 18 are formed merely by grooving the cooperating surfaces of the head and body and can be of any size desired.

35 My invention is believed to overcome the objections heretofore existing in air compressors and to provide a more simple, cheap and efficient compressor than has heretofore been known.

Having thus described my invention, what 40 I claim is:

1. An air compressor comprising the combination of a body having a pair of cylinders therein, a piston in each cylinder, a removable head closing the outer ends of the cylinders, a pair of outlet valves in the head respectively over the ends of the cylinders, said cylinder body being provided with two inlet valve chambers and seats, and being also provided with a bore forming intakes to 50 the chambers, a pair of inlet valves resting on the seats and having stems extending into and guided by the head, a spring around each stem between each valve and head, said cylinder body being also provided with 55 grooves between the body and head providing communication from the intake valves to the cylinders.

2. An air compressor comprising the combination of a body having a pair of cylinders formed therein, a piston in each cylinder, a removable head closing the outer ends of the cylinders, a pair of outlet valves in the head respectively over the ends of the cylinders, a stem on each valve projecting into 60 the head and guided thereby, a spring surrounding each stem and interposed between the head and the valves, said cylinder body having formed therein two inlet valve chambers and seats in the body between the cylinders, said cylinder body having also formed therein a bore forming intakes to the 65 chambers, and a pair of inlet valves resting on the valve seats, said cylinder body having formed therein grooves between the body 70 and the head providing communication from the intake valves to the cylinders.

ALBERT G. LARSON.
